UNITED STATES PATENT OFFICE.

JOHN W. OGILBEE, OF PORTLAND, OREGON.

DESIGN FOR A KEY FASTENER AND RING.

SPECIFICATION forming part of Design No. 24,864, dated November 5, 1895.

Application filed September 12, 1895. Serial No. 562,335. Term of patent 7 years.

To all whom it may concern:

Be it known that I, JOHN W. OGILBEE, a citizen of the United States, residing at Portland, in the county of Multnomah and State of Oregon, have invented and produced a new and original Design for a Key-Fastener and Key-Ring, of which the following is a full, clear, and exact description.

Reference is to be had to the accompanying drawings, forming a part of this specification, in which—

Figure 1 is a side view of a key-fastener and key ring embodying my new design, and Fig. 2 is an edge view thereof.

The leading feature of my design consists

in the key-ring and fastener having a contraction near one end, presenting a loop formation outward and inward from such contraction, and the elongated arms departing from the innermost loop formation.

20

A subordinate feature of the design resides in the widened outer ends of the arms, said widened ends tapering to points.

I claim—

The design for a key fastener and key ring 25 herein shown and described.

JOHN W. OGILBEE.
